(Cl. D44—1)

To all whom it may concern:

Be it known that I, Nathan W. Roop, a citizen of the United States, residing at Columbus, in the county of Franklin and State of Ohio, have invented a new, original, and ornamental Design for an Ice Cube Storing and Dispensing Receptacle or Similar Article, of which the following is a specification, reference being had to the accompanying drawing, forming a part thereof.

Fig. 1 is a perspective view of an ice cube storing and dispensing receptacle or similar article showing my new design;

Fig. 2 is a front elevational view;

Fig. 3 is a top plan view;

Fig. 4 is a bottom plan view; and

Fig. 5 is a partial vertical sectional view thereof.

I claim:

The ornamental design for an ice cube storing and dispensing receptacle or similar article, substantially as shown.

NATHAN W. ROOP.
